(57) **CLAIM**

The ornamental design for a handle for a cleaning implement, as shown and described.

DESCRIPTION

FIG. 1 is a rear left perspective view of handle for a cleaning implement, wherein the remainder of the cleaning implement is unclaimed and omitted for clarity;

FIG. 2 is a front view thereof;

FIG. 3 is a top view thereof;

FIG. 4 is a right view thereof;

FIG. 5 is a rear view thereof;

FIG. 6 is a left view thereof; and,

FIG. 7 is a bottom view thereof.

The dot-dash-dot broken line showing represents unclaimed boundaries of the claimed design. The dot-dot broken line showing represents environmental structure and forms no part of the claimed design.
